UNITED STATES PATENT OFFICE

2,049,274

PRINTING PRESS FOR PRINTING WAX CARBON SPOTS ON SHEETS OF PAPER

Alexander B. Roe, Athens, Ohio

Application October 9, 1934, Serial No. 747,543

16 Claims. (Cl. 101—335)

My invention relates to that class of presses designed to do the work such as is described in United States Letters Patent No. Re. 18,931 issued to George A. Rutkoskie. In that patent the wax carbon compound is melted and the various parts of the press are heated by means of electricity. This produces a satisfactory press and turns out satisfactory work but the cost of electricity as compared with other forms of heating means is quite considerable.

My present invention has for its object to construct a press which is preferably heated by steam, although it may be heated by hot water. It has been discovered that the wax carbon compound must be handled at a critical temperature or it will entirely fail in producing necessary results.

I am aware of the fact that it has been proposed to use steam or hot water for the heating of parts of printing presses for this purpose but so far as I am aware none of them have proven satisfactory in use. I have discovered that the reason for this is owing to the feature to which I have directed attention, to wit: the critical temperature at which the wax carbon compound must be handled. It has been found in practice that if this temperature varies even slightly, unsatisfactory work is turned out by the press. It is also necessary that this temperature be maintained in all of the parts of the press which contact the wax carbon compound. As the travel for the steam or hot water is considerable, more or less, condensation takes place which results in cooling of the parts of the press and consequently faulty work is turned out.

My invention has for its further object to provide means for heating a press designed to handle melted wax carbon compound for printing wax carbon spots on sheets of paper in which means are provided to insure a continuous flow of the heating medium employed thereby maintaining the temperature at any predetermined point.

My invention has for its further object to provide means for maintaining the temperature of the supply of heating medium and to hold this temperature at a predetermined point.

My means of accomplishing the foregoing objects may be more readily understood by having reference to the accompanying drawings which are hereunto annexed and are a part of this specification in which—

Fig. 1 is a top or plan view of a press equipped with my improved heating means;

Fig. 2 is an enlarged detailed view of the type

bed partly in section to show the interior construction;

Fig. 3 is a section taken on the line 3—3 in Fig. 2;

Fig. 4 is a fragmentary view of the press opened 5 showing the means of heating the operating parts of the press;

Fig. 5 is a detail end view showing the manner of mounting the supply pipes for the type bed;

Fig. 6 is a side elevation of the same; 10

Fig. 7 is a detailed view partly in section showing the manner of supplying the rollers with the heating medium;

Fig. 8 is a fragmentary detail view showing the 15 manner of heating the ink fountain;

Fig. 9 is a more or less diagrammatic view showing the method of insuring a continuous flow of the heating medium.

Similar reference numerals refer to similar parts throughout the entire description. 20

As shown in the drawings I have illustrated a press of the Kelly type. As this construction is so well known I shall confine my description to those parts of it which are provided with special attachments so as to permit of its use in printing 25 spots of wax carbon compound on sheets of paper.

As shown in Fig. 1 the press is equipped with a type bed 1, form rollers 2 and 3, distributor roller 4, ink fountain roller 5, ductor roller 6, vibrator roller 7 and ink fountain 8. 30

As shown in Fig. 2 of the drawings, the heating medium is introduced into the type bed 1 by means of a pipe 9 which extends into a compartment 10. A number of these compartments are cast or formed in the type bed 1. The walls 11 35

and 12 of the compartment 10 terminate a short distance from the end 13 of the type bed 1 so as to permit the heating medium to flow as indicated by the arrows into the compartment 14 40 located in the right hand side. A port or passage 15 in the wall 16 of the compartment 14 is provided for the flow of the heating medium from compartment 14 into compartment 17. The termination of the wall 12 also allows the heating 45

medium to flow into compartment 18 formed at the left hand side of compartment 10. The compartments 17 and 18 are connected by ports or passages 43 and 44 which permit the heating medium to find access to a chamber 45 formed in the ink 50 plate 46. The pipe 9 is mounted in a sleeve 19 which is secured to the front end 20 of the type bed 1, as shown it is fastened by means of bolts 21 which provide a tight joint between the flange 22 on the end of the sleeve 19 and the type bed 55

1. The sleeve 19 is mounted for reciprocation in a cylinder 23, a packing gland 24 of suitable construction being provided to prevent the escape of fluid from the chamber 25 as the type bed 1 moves back and forth due to the reciprocation imparted to it by the operation of the press.

5 The cylinder 23 is carried by an arm 26 which is bolted or otherwise secured to the frame 27 of the press. The upper part of the arm 26 as clearly seen in Fig. 5 is divided to form a split block the upper half 28 of which is secured by bolts 29 to the lower part of the block. This serves to hold the cylinder 23 in alignment when the type bed is reciprocated and the sleeve 19 moves back and forth within the cylinder 23. In some cases it may be found desirable to substitute a flexible hose for the cylinder and sleeve shown, obviously this would be a mechanical equivalent of the structure described.

10 20 The ink fountain 8 is provided with a coil of pipes 30 which extend backwards and forwards through the ink fountain to melt the wax carbon and also to secure the required uniform temperature of the wax carbon compound.

15 25 As seen in Fig. 7 I have illustrated the manner of heating the ink fountain roller. As the means employed to heat the other rollers are identical I shall only describe a single one. The roller 5 is formed with a central hollow space 31 which is closed by means of a plug 32 which is screw threaded into the roller 5. This plug carries an outwardly extending sleeve 33 which extends into a cylinder 34, a suitable packing gland 35 being provided which will compress the packing and make a tight joint between the cylinder 34 and the external wall of the sleeve 33. A pipe 36 is provided to convey the heating medium to the interior of the roll 5, the end 37 of which terminates a short distance from the end 38 of the hollow space 31. This permits the heating medium to flow from the pipe 36 into the space intermediate the internal surface of the sleeve 33 and the external surface of the pipe 36 into a chamber 39 whence it escapes by means of a pipe 40 back to the boiler.

40 45 As shown in Fig. 4 I provide a plurality of pipes 41 which pass through the press adjacent the rollers and a protective shield 42 in order to maintain the parts which contact with the carbon at the required temperature.

50 55 In Fig. 9 I have shown connections for conveying the heating medium from the boiler to the various parts of the press. As shown in the drawings which is more or less diagrammatic, the steam or other heating medium flows through the pipes as indicated by the arrows coming from the boiler (not shown) it passes through pipe 47 through a valve 48 and a standard regulator 49 into pipe 50. This pipe is suitably connected by means of pipes 51 and 52 to the rollers 3 and 5 or any other rollers which are to be heated. Pipe 53 is connected to the coil 30 in the ink fountain 8. Pipe 54 is connected to pipe 41 for heating the various parts of the press. All of these pipes are suitably connected to return pipes 55 and 56.

60 65 70 Flow and return pipes 57 and 58 are suitably connected to pipes 50 and 55 and carry the heating medium used to heat the type bed 2 of the ink plate 46. The return pipes 55 and 56 are joined together at 59 and are suitably connected to a circulating pump 60 of any desired type. As illustrated the pump is driven by a motor 61 suitably connected by means of a belt 62 to the pump 60.

75 Operation of the pump serves to draw the heating medium continuously from the return pipes and discharges it through the discharge side of the pump 60 by means of pipe 63 to a pre-heater 64 which may be connected to the boiler 5 (not shown) or by means of a pipe 65. It will be apparent from this description that I have provided means whereby the operation of the pump 60 produces a constant flow of the heating medium employed which will be maintained 10 throughout all of the various parts of the press as long as the pump is operated. By the utilization of the regulator 49 I am able to maintain the temperature of the heating medium, employed, at any predetermined degree.

15 Having described my invention what I regard as new and desire to secure by Letters Patent is:

1. In a press for printing wax carbon spots on sheets of paper having an ink plate, type bed, ink fountain, and a plurality of rolls; means to supply a heating medium to the interior of said ink plate, type bed, ink fountain, and rolls, means separate from said supply means to return the heating medium to its supply, and means to maintain a continuous circulation of the heating 25 medium through said rolls.

2. In a press for printing wax carbon spots on sheets of paper, a plurality of rolls in said press, means to supply a heating medium to the interior of said rolls, means separate from said supply 30 means to return the heating medium to its supply, a reciprocating type bed in said press, said bed being provided with a plurality of compartments, means to connect said compartments to the flow of the heating medium, separate means 35 to convey the heating medium back to its source, and means to maintain a continuous circulation of the heating medium through said rolls and type bed.

3. In a press for printing wax carbon spots on 40 sheets of paper, an ink plate, a reciprocating type bed connected to said ink plate, said bed being provided with a plurality of compartments some of which lead to said ink plate, means to supply a heating medium to said compartments, separate 45 means to convey the heating medium back to its source, and means to maintain a continuous circulation of the heating medium through said type bed.

4. In a press for printing wax carbon spots on 50 sheets of paper, a plurality of rolls in said press, means to supply a heating medium to the interior of said rolls, means separate from said supply means to return the heating medium to its source, a reciprocating type bed in said press, said bed 55 being provided with a plurality of compartments, means to connect said compartments to the flow of the heating medium, separate means to convey the heating medium back to its supply, an ink fountain in said press, means to circulate a 60 heating medium through said ink fountain, and means to maintain a continuous circulation of the heating medium through said rolls, type bed, and ink fountain.

5. In a press for printing wax carbon spots on 65 sheets of paper, a plurality of rolls in said press, means to supply a heating medium to the interior of said rolls, means separate from said supply means to return the heating medium to its source, a reciprocating type bed in said press, said bed 70 being provided with a plurality of compartments, telescopic means to connect said compartments to the flow of the heating medium, separate means to convey the heating medium back to its supply, and means to maintain a continuous cir- 75

- ulation of the heating medium through said rolls and type bed.
6. In a press for printing wax carbon spots on sheets of paper, a plurality of rolls in said press, means to supply a heating medium to the interior of said rolls, means separate from said supply to return the heating medium to its source, a reciprocating type bed in said press, said bed being provided with a plurality of compartments, telescopic means to connect said compartments to the flow of the heating medium, means separate from said flexible means to convey the heating medium back to its supply, means to maintain a continuous circulation of the heating medium through said rolls and type bed, said flexible means comprising a cylindrical sleeve secured to one end of said type bed, a cylinder in which said sleeve is reciprocated, a pipe mounted in said compartments.
- 20 7. In a press for printing wax carbon spots on sheets of paper, a plurality of rolls in said press, means to supply a heating medium to the interior of said rolls, means separate from said supply means to return the heating medium to its supply, and means to maintain a continuous circulation of the heating medium through said rolls, automatic means to maintain the temperature of said heating medium at a predetermined temperature.
- 25 8. In a press for printing wax carbon spots on sheets of paper, a plurality of rolls in said press, means to supply a heating medium to the interior of said rolls, means separate from said supply means to return the heating medium to its source, a reciprocating type bed in said press, said bed being provided with a plurality of compartments, means to connect said compartments to the flow of the heating medium, separate means to convey the heating medium back to its supply, means to maintain a continuous circulation of the heating medium through said rolls and type bed, and automatic means to maintain the temperature of said heating medium at a predetermined temperature.
- 30 9. In a press for printing wax carbon spots on sheets of paper having a plurality of rolls, a reciprocating type bed in said press, said bed being provided with a plurality of compartments, means to supply a heating medium to said compartments, separate means to convey the heating medium back to its supply, means to maintain a continuous circulation of the heating medium through said rolls and type bed and automatic means to maintain the temperature of said heating medium at a predetermined temperature.
- 35 10. In a press for printing wax carbon spots on sheets of paper having rolls, a reciprocating type bed, and an ink fountain; means to supply a flow of fluid heating medium to said rolls, type bed, and ink fountain, means separate from the supply means to return the fluid to its supply, means to maintain a continuous circulation of the heating medium through said flow and return means, and automatic means to maintain said fluid at a predetermined temperature.
- 40 11. In a press for printing wax carbon spots on sheets of paper having a plurality of rolls, a reciprocating type bed in said press, said bed being provided with a plurality of compartments, so divided as to provide a circuitous but continuous passage way below the entire surface of said type bed, means to supply a heating medium to said compartments, separate means to convey the heating medium back to its supply, and means to maintain a continuous circulation of the heating medium through said rolls and type bed.
- 45 12. In a press for printing wax carbon spots on sheets of paper, a reciprocating type bed in said press, said bed being provided with a plurality of compartments, means to supply a heating medium to said compartments, separate means to convey the heating medium back to its supply, and means to maintain a continuous circulation of the heating medium through said rolls and type bed, a hollow ink plate adjacent said type bed, there being passages to connect the interior of the ink plate to the compartments in the type bed.
- 50 13. In a press for printing wax carbon spots on sheets of paper having an ink plate, reciprocating type bed, ink fountain, and a plurality of rolls; means to supply a heating medium to the interior of said rolls, a fluid tight telescopic connection to convey said heating medium to the interior of said rolls and reciprocating type bed, and means to maintain a continuous circulation of the heating medium through said rolls.
- 55 14. In a press for printing wax carbon spots on sheets of paper, a plurality of rolls in said press, means to supply a heating medium to the interior of said rolls, a reciprocating type bed in said press, said bed being provided with a plurality of compartments, means to connect said compartments to the flow of the heating medium, and means to maintain a continuous circulation of the heating medium through said rolls and type bed.
- 60 15. In a press for printing wax carbon spots on sheets of paper, a reciprocating type bed in said press, said bed being provided with a plurality of compartments, means to supply a heating medium to said compartments, means to maintain a continuous circulation of the heating medium through said type bed and telescopic means to connect said compartments to said supply of heating medium.
- 65 16. In a press for printing wax carbon spots on sheets of paper, a plurality of rolls in said press, means to supply a heating medium to the interior of said rolls, a reciprocating type bed in said press, said bed being provided with a plurality of compartments, means to connect said compartments to the flow of the heating medium, an ink fountain in said press, means to circulate a heating medium through said ink fountain, and means to maintain a continuous circulation of the heating medium through said rolls, type bed, and ink fountain.

ALEXANDER B. ROE.
